US00D779296S

(12) **United States Design Patent** (10) **Patent No.:** **US D779,296 S**
(45) **Date of Patent:** **** Feb. 21, 2017**

(54) **MULTIPLE WRENCH TOOL**

(71) Applicant: **Home Depot Product Authority, LLC,**
Atlanta, GA (US)

(72) Inventor: **Nicole Runnels**, Atlanta, GA (US)

(73) Assignee: **Home Depot Product Authority, LLC,**
Atlanta, GA (US)

(**) Term: **15 Years**

(21) Appl. No.: **29/565,366**

(22) Filed: **May 19, 2016**

Related U.S. Application Data

(63) Continuation of application No. 13/613,537, filed on
Sep. 13, 2012.

(51) **LOC (10) Cl.** **08-05**

(52) **U.S. Cl.**
